UNITED STATES PATENT OFFICE.

GEORGE J. CAPEWELL, OF HARTFORD, CONNECTICUT.

DESIGN FOR A RAILWAY-RAIL.

SPECIFICATION forming part of Design No. 29,833, dated December 20, 1898.

Application filed November 26, 1898. Serial No. 697,565. Term of patent 14 years.

To all whom it may concern:

Be it known that I, GEORGE J. CAPEWELL, a citizen of the United States, residing at Hartford, in the county of Hartford and State of Connecticut, have invented a certain new and original Design for Railway-Rails, of which the following is a specification.

Of the accompanying drawings, to which reference is made and which form a part of this specification, Figure 1 is a plan of a short length of rail formed after my design, and Fig. 2 is a transverse section of the rail that embodies my design.

As shown in the drawings, the leading or material feature of my design consists of two

flat-faced treads 1, between which treads rises a vertical web 2, and from the outer edges of which treads depend sides 3, that have along their lower edges outwardly-extending flanges 4.

Having now described my invention, what I claim as new, and desire to secure by Letters Patent, is—

The design for a railway-rail, as herein shown and described.

GEORGE J. CAPEWELL.
